UNITED STATES PATENT OFFICE.

JOHN SMITH, OF KANSAS CITY, MISSOURI.

FASTENING FOR CORRUGATED METAL SHEETS.

SPECIFICATION forming part of Letters Patent No. 297,862, dated April 29, 1884.

Application filed February 29, 1884. (No model.)

To all whom it may concern:

Be it known that I, JOHN SMITH, a citizen of the United States, residing at Kansas City, in the county of Jackson and State of Missouri, have invented certain new and useful Improvements in Fastenings for Corrugated Metal Sheets; and I hereby do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in the manufacture of corrugated metal sheets, and in securing them in place upon buildings.

It consists of using hook-shaped fastenings instead of nails, and, further, of stamping depressions in the edge of the sheets, which depressions are adapted to fit over hooks previously attached to the timbers of a building, so that said hooks shall not prevent the overlapping sheets making a snug joint with the 25 sheet underlying it.

Figure 1 represents a plan view of two corrugated metal sheets, one overlapping the other, and having a corner cut away, each being held in place upon a piece of timber by my improved fastenings. Fig. 2 shows in perspective one hook properly fixed to a piece of sheeting or siding with one corner of a metal sheet inserted beneath the hook end thereof. Fig. 3 is an end view, showing how 30 two sheets are joined sidewise and held in position by means of a curved fastening. Fig. 35 4 shows the end of a corrugated metal sheet having the stamped depressions for the reception of that part of the fastening beneath which the edge of the initial or lower sheet is 40 inserted.

Referring again to the drawings, A represents a fastening, constructed preferably of wrought-iron, having one end flattened and 45 suitable holes punched therein for attaching it to the timber of a building by means of screws or nails, and the other turned to form a short hook.

Sheets of metal are prepared by running 50 them through a corrugating-machine having suitable dies upon the rolls that form the de-

pressions B along the corrugated edges of the sheets.

In applying my improved sheets to a building, as in Fig. 1, a sheet is laid. Then a sufficient number of the straight hooks A are attached to the timbers or sheeting S at such distance apart as will correspond to every other concave depression in the corrugated sheet E. Then the overlapping sheet D, having depressions B along its lower edge, is placed in the position shown, the indentations or depressions B fitting within the short hooked ends of the fasteners A. As before stated, these indentations are to make room for the 55 fasteners, so that the overlapping sheet D will not be held away from the sheet E. Any number of sheets may be thus applied, and their straight edges are secured by means of hooks C, curved to fit the corrugations, and 60 fastened to the timbers, as before described. They may be placed any suitable distance from each other, and in applying them, a line of sheets having been run up the building, the hooks C are placed so that the curved 65 ends thereof fit across the outside convex edge of the sheets, and upon applying another course of sheets the edges of such course lap over those previously laid, and are held in such position by the short hooks upon the 70 curved end of side fastenings, C.

By the application of my improved metal sheets, leaky nail-holes and nails are entirely dispensed with, and the sheets are free to expand or contract with the varying temperatures and conditions in which it may be placed. 75 When the under side of the sheets become rusty or corroded, they may easily be taken off, painted, and reversed. With a common sheet roof or siding or an inside ceiling this 80 cannot be accomplished.

The fastenings can be applied to iron rafters of buildings by means of bolts or rivets. They may also be used in fastening slate.

Having thus described my invention, I claim 95 as new and desire to secure by Letters Patent—

1. A corrugated metal sheet having depressions or indentations B stamped or rolled upon one edge or side, such indentations being situated within the longitudinal concavities of the sheet, substantially as shown and described.

2. In corrugated sheets of metal for roofs of buildings, the sheet D, having impressions B fixed along one edge or side, longitudinal fastenings A, secured to timber S, and side fastenings, C, curved as shown, all substantially as described, and for the purposes herein set forth.

In testimony whereof I affix my signature in presence of two witnesses.

JOHN SMITH.
